VEST

Larry R. Engelson, New York, N. Y.

Application October 5, 1937, Serial No. 167,340

7 Claims. (Cl. 2—102)

This invention relates to vests and constitutes an improved construction for a like invention set forth in my prior Patent No. 2,099,054, granted November 16, 1937.

5 One of the main objects of the invention resides in a vest or like garment which may be adjusted to various sizes by the wearer. Such feature will be found most useful in the construction of men's dress vests, for the owner of 10 such garment may have only occasional use for the same and during the life of the vest, the owner may adjust the same to meet varying changes in his body measurements. Such a vest is capable of long use by the owner with assurance of a perfect fit at all times.

Another feature of the invention is to provide an adjustable vest that permits a merchant carrying a large variety of patterns without unduly burdening his stock as would necessarily result if 15 the same number of patterns or styles of vests were carried in the relatively wide range of lengths necessary to provide a complete stock of lengths within the range.

A further feature of the invention is the provision of a dress vest having a separate neck strap, the ends of which are adjustably connected to the top portions of the vest sections in a novel manner as to be concealed from view and yet be 20 readily accessible to the wearer for adjustment 25 purposes.

Other features of the invention will be apparent as the following specification is read in conjunction with the accompanying drawing, in which:

Figure 1 is a perspective view of a dress vest 35 constructed in accordance with one embodiment of my invention.

Figure 2 is an enlarged fragmentary plan view of the top end of one of the vest sections with part of the lapel broken away to illustrate the 40 adjustable fastening means.

Figure 3 is an enlarged horizontal sectional view on the line 3—3 of Figure 2.

Figure 4 is a fragmentary perspective view illustrating releasable engaging means for securing 45 the lapel.

Figures 5 and 6 are fragmentary perspective views of modified embodiments of the invention.

Figure 7 is a plan view of a set of different size 50 collar straps which may be used in lieu of a single adjustable strap for length adjustment.

Referring to the drawing by reference characters, the numeral 10 designates my adjustable dress vest in its entirety which includes two body sections 11—11 buttonable at the front as at 12'. 55 The body sections 11—11 are of similar construction and each has a front turned back lapel 12 associated therewith, the lapel in each case overlying a portion of its respective body section to provide a space 13 between the outer face of 60 the body section and the under or inner face of

its respective lapel. The lapel 12 tapers upwardly from its bottom and the outer corner of the narrow top end of the lapel is tacked by stitching 14 to its associated body section 11. By securing the top corner of the lapel 12 to the body section 11, there is formed a loop or tunnel entrance 15 to the space 13 and prevents bending back or opening of the top of the lapel to avoid disclosing the adjusting means presently to be described.

The body sections 11—11 are separate from each other, there being no back or side sections such as generally provided in dress vests. Whereas the body sections 11—11 are secured together by the button means 12' after the garment has been fitted to the wearer, they are also connected together at their top portions so as to join the sections together and form a vest unit and this phase of the invention will now be described.

Stitched to each body section 11 beneath the top end of the lapel 12 adjacent to but slightly below the plane of the tack stitching 14 is a button 16, the same being concealed beneath the lapel but being accessible to the fingers of a wearer of the vest when inserting them upwardly into the space 13 between the lapel and the body section.

Insertible through the loops or tunnels 15 of the body sections 11—11, are the ends of a neck or collar strap 17, the said ends having spaced button holes 18 therein for selective engagement with the buttons 16 of the respective body sections.

By selectively engaging the button holes 18 with the respective buttons 16, the body sections 11—11 may be raised or lowered to fit the body of the wearer. Such adjustment may be readily made by the wearer for the buttons 16 are within easy reach, although concealed from view by the lapels 12. By concealing the adjustable fastening means of the neck strap 17, the unsightly appearance of the same is eliminated and which might otherwise show even though the wearer may have on a dinner or formal evening coat.

For pulling the body sections 11—11 inwardly 45 against the body of a wearer, the lower portions of the same are connected by an adjustable waist strap 19.

In Figure 4 of the drawing, I have illustrated a modified means of securing the top corner edge 50 of the lapel 12 to the body section 11. Instead of permanently securing the corner edge of the lapel to the body section 11 by stitching, I employ separable means in the form of hook and eye fastener members 20 and 21 stitched to the lapel 55 and body section respectively, or as illustrated in Figure 6, male and female snap fastener elements 22 and 23 may be employed. By releasably fastening the lapel to the body section, the lapel may be opened as shown in Figures 4 to 6 inclu- 60

sive to gain easy access to the strap fastening means.

In Figure 5 I have illustrated a modified form of collar strap adjusting means wherein a buckle 5 24 is secured to the body section 11 beneath the lapel 12 to receive the end of a fabric neck strap 25.

In Figure 6 a further modified form of strap adjustment is shown wherein a male snap fastener member 26 may be stitched to the body section 11 instead of a button and engaged by any one of a plurality of female snap fastener members 27 stitched to the underside of each end of a collar strap 28.

15 From the foregoing description read in conjunction with the accompanying drawing, it will be apparent that the present invention provides a new and improved vest or like garment which is so constructed that it may be adjusted to various 20 sizes and lengths and that such result may be accomplished in a single, inexpensive, and easy manner.

In Figure 7 of the drawing, there is shown a set of three collar straps 29, 30, and 31, of progressively different predetermined lengths and the same being respectively termed long, regular, and short sizes. Each of these collar straps is provided with but a single buttonhole 32 adjacent each end instead of a plurality of predeterminedly spaced button holes 18 present in the adjustable collar strap 17. In this embodiment of the invention, a vest consisting of the body sections 11-11 similar to that shown in Figures 1 to 3 may be sold to a buyer with a set of different size collar straps 29, 30, and 31. The set of collar straps are interchangeable to suit the length of the wearer and may be substituted one for the other as the body measurements of a wearer may vary. The button holes 32 of the individual straps are engaged with the buttons 16 in the same manner as the selected buttonhole 18 of the strap 17.

While I have illustrated the straps 29, 30, and 31 as being provided with buttonholes, the same 45 may be detachably connected to the body sections 11-11 in the same manner as illustrated in Figure 6, wherein snap fasteners may be substituted for button and buttonholes.

Having thus described the invention, what I 50 claim as new and desire to secure by Letters Patent of the United States, is:—

1. A vest comprising two separate body sections, a lapel carried by each of said body sections, each of said lapels overlying a portion of its respective body section, fastening means provided at the outer top corner edge of each lapel to secure the same to its associated body section, a collar strap having its ends disposed beneath the top portions of the lapels on said body sections, and releasable fastening means carried beneath each lapel and concealed thereby and securing the ends of said collar strap and the respective body sections together.

2. A vest comprising two separate body sections, a lapel carried by each of said body sections, each of said lapels overlying a portion of its respective body section, fastening means provided at the outer top corner edge of each lapel to secure the same to its respective body section and providing a tunnel entrance to the space between said lapel and its associated body section, a button carried by each of said body sections.

beneath the lapel carried thereby adjacent the top thereof, and a collar strap having its ends inserted through the respective tunnel entrances of the body sections so as to lie beneath the lapels, said collar strap having button openings near each end thereof for engagement with the aforementioned buttons carried by the body sections.

3. A vest comprising two separate body sections, a lapel carried by each of said body sections, each of said lapels overlying a portion of its respective body section, stitching securing the outer top corner edge of each lapel to its respective body section and providing a tunnel entrance to the space between said lapel and its associated body section, a button carried by each of said body sections beneath the lapel carried thereby adjacent the top thereof, and a collar strap having its ends inserted through the respective tunnel entrances of the body sections so as to lie beneath the lapels, said collar strap having button openings near each end thereof for engagement with the aforementioned buttons carried by the body sections.

4. A vest comprising two separate body sections, a lapel carried by each of said body sections, each of said lapels overlying a portion of its respective body section, fastening means securing the outer top corner edge of each lapel to its associated body section, a buckle fixedly secured to each body section and underlying its associated lapel adjacent the top thereof, and a collar strap having its ends disposed beneath the respective lapels and secured to said body sections by the buckles carried thereby.

5. A vest comprising two separate body sections, a lapel carried by each of said body sections, each of said lapels overlying a portion of its respective body section, fastening means provided at the outer top corner edge of each lapel to secure the same to its associated body section, a collar strap having its respective ends disposed beneath the lapels, and separable fastener elements carried by said body sections beneath the lapels for securing the ends of said strap to said body sections.

6. A vest comprising two separate body sections, a lapel carried by each of said body sections, each of said lapels overlying a portion of its respective body section, a button carried by each of said body sections beneath its associated lapel, fastening means securing the outer top corner edge of each lapel to its associated body section, a removable collar strap of a predetermined length having a single opening adjacent each of its ends and receiving the buttons carried beneath the lapels.

7. A vest comprising two separate body sections, a lapel carried by each of said body sections, each of said lapels overlying a portion of its respective body section, fastening means provided at the outer top corner edge of each lapel to secure the same to its associated body section, a collar strap having its ends disposed beneath the top portions of the lapels on said body sections, one of the ends of said collar strap being fastened to one of said body sections, and releasable adjustable fastening means carried beneath the lapel of the other body section for adjustably securing the other end of said collar strap thereto.

LARRY R. ENGELSON.
